UNITED STATES PATENT OFFICE

CLIFFORD SKLAREK, OF CHICAGO, ILLINOIS, ASSIGNOR TO INTERNATIONAL SPOT-LIGHT CORPORATION, OF CHICAGO, ILLINOIS, A CORPORATION OF ILLINOIS

FOCUSING DEVICE

Original application filed May 25, 1927, Serial No. 194,022. Divided and this application filed June 6, 1928. Serial No. 283,208.

This invention relates to improvements in focusing devices, and is a division of my pending application Ser. No. 194,022, filed May 25, 1927.

In the manufacture and use of dirigible lights, the most common use of which is as a spotlight for automobiles and other automotive vehicles, one of the most difficult things to attain is a satisfactory projection of a powerful beam of light. The small electric bulbs which are universally used in this type of light as a source of illumination in combination with a reflector are not manufactured commercially of uniform character, it being a well known fact that the filaments are more or less irregular and very frequently off center with respect to the base of the bulb so that, even though the socket for the bulb is accurately placed relatively to the reflector, the light rays will not emanate from the focus of the reflector surface and consequently a relatively weak and diffused beam of light is the result. This has been found true even when relatively high candle power bulbs are used.

One object of my invention therefore is to provide simple and efficient adjustable means in the lamp head of a dirigible light for compensating for irregularities in the location 30 of the filaments of the electric bulb so that the source of illumination may be accurately disposed at the focus of the reflector for any electric bulb that may be used in the lamp head.

Other and further objects of the invention will more clearly appear from the description and claims hereinafter following.

In the drawings forming a part of this specification, Figure 1 is a part elevational view, part vertical, sectional view, of a lamp showing my improvements incorporated therein. Figure 2 is an enlarged, vertical, sectional view illustrating the details of construction of the adjustable means for the bulb socket. Figure 3 is a vertical, sectional view corresponding to the line 3—3 of Figure 2 but upon a somewhat smaller scale. And Figure 4 is a sectional view of a modified form of the adjusting arrangement for the electric bulb and embodying the invention.

As shown in Figures 1 to 3 of the drawings, the lamp head comprises a main outer shell 5 of more or less parabolic outline, the lower portion of the shell being secured between two washers 6 and 7 by a nut 8 to a vertically extending operating shaft 9. The lamp shell is provided with a lens 10, attached to the shell by suitable means such as the clamping ring 11, and screws 12. Within the shell 5 there is provided a reflector 13, the one illustrated being of the usual parabolic type such that all light rays emanating from the focus of the reflector will be reflected from the surface of the reflector in parallel lines. Access to the interior space between the rear wall of the shell 5 and the reflector 13 is obtained through a large screw cap 14, which may be conveniently turned by a coin or other suitable device, the cap 14 being located at the apex of the shell and alined with the axis 70 of the lamp.

As customary in this type of light, I employ an electric bulb 15, which is indicated conventionally, the same having a filament shown at 16, and the usual base 17, the latter being provided with the usual pins not shown, adapted to be assembled with the sleeve or socket member 19 in the usual manner through the medium of a bayonet-slot indicated at 20.

The socket 19 is slidably mounted in the direction of its axis within a holder in the form of an adjustable sleeve 21, the details of which are best shown in Figure 2. The adjustable sleeve 21 is, in turn, rotatably mounted within a support in the form of a block 22 rigidly secured to the reflector 13, as shown. The sleeve 19 is provided with an axially extending flange 23 which is slotted so as to provide a plurality of spring fingers 24. The fingers 24 frictionally engage the socket member 19 and thus frictionally hold the latter in any adjusted position axially of the adjusting sleeve 21. The sleeve 21, as shown in the drawings, has the opening, indicated at 25, which receives the socket member 19, eccentrically disposed with respect to the outer cylindrical surface 26 of the adjusting sleeve 21 so that, as the adjusting sleeve is rotated, the axis of the socket mem- 100

ber 19, and consequently, the axis of the electric bulb 15, will be shifted up and down and laterally so that the center of the filament 16 may be accurately adjusted to co-incide with the focus of the reflector, regardless of variations in the location of the filament relative to the axis of the base of the bulb. With the two adjustments, that is, the longitudinal and radial adjustments described, I am enabled to bring the source of illumination to the exact focus of the reflector and thus obtain true parallel reflecting light rays and a most powerful light.

To maintain the adjusting eccentric sleeve 21 in any adjusted position of rotation, I preferably employ a spring yoke 27, which is secured to the bearing member 22 by a screw 28, the spaced arms 29—29 of the yoke, carrying at their lower ends, inwardly extending pins 30—30, passed through diametrically alined openings in the bearing block 22, the inner ends of said pins being rounded, as shown, engaging within an annular groove 31 formed in the circumference of the adjusting sleeve 21. In this manner, sufficient friction is created to retain the adjusting sleeve 21 in any angular position in which the same is set. In this connection also, I utilize the pins 30 for an additional purpose. As best shown in Figure 2, the bearing sleeve 21 is provided with a radially extended flange 32 which bears against the outer face of the bearing 22. The pins 30—30 are so located with respect to the wall of the groove 31 as shown in dotted lines in Figure 2 as to be off center with respect to the groove 31 and toward the forward or inner side thereof, thereby camming or pulling the adjusting sleeve 21 inwardly with respect to the bearing 22, and thereby maintaining the parts in tight engagement with each other to avoid rattling or loose play. As will be understood, the inner ends of the pins 30—30 are round so as to facilitate the action last described. For convenience the peripheral edge of the flange 32 may be knurled so as to facilitate rotation of the sleeve 21 by the operator's fingers which may be inserted through the opening in the rear of the shell when the cap 14 is removed.

Referring now to the embodiment of the invention shown in Figure 4, in lieu of the eccentrically adjustable bearing for the bulb socket, I may employ an adjustable supporting sleeve 121 having an annular rib 122 of spherical formation, the surfaces of which co-operate with a bearing member 123, secured to the reflector 113, and an annular bearing ring 124. The bearing member 123 and the ring 124 are provided with complementary spherical bearing surfaces co-operable with the bearing surfaces of the rib 122 to form a ball and socket joint so that the sleeve 121 may be adjusted universally to vary the axis of the lamp socket. To maintain the ad-

justed position of the sleeve 121 and to eliminate possibility of rattling, the ring 124 is attached to the bearing 123 by screws 125—125, the latter carrying springs 126—126 on their stems interposed between the heads of the screws and the ring 124. The adjustable sleeve 121 is provided with spring fingers 127 corresponding to the spring fingers 24 of the structure first described so as to frictionally hold the socket 128 in any adjusted position in an axial direction relative to the supporting sleeve 121. As will be apparent, I am enabled to obtain the same universality of the adjustment of the filament of the lamp with respect to the reflector as heretofore described in connection with the structure shown in Figures 1 to 3.

While I have herein shown and described what I now consider the preferred manner of carrying out my invention, the same is merely illustrative and I contemplate all changes and modifications that come within the scope of the claims appended hereto.

I claim:

1. In a lamp including a reflector and a lamp bulb cooperating with the reflector, the combination with a socket adapted to receive the lamp bulb; of means for supporting said socket including a sleeve receiving said socket, and a fixed block forming a holder for the sleeve, said sleeve being laterally adjustable in said block, and said socket being adjustable lengthwise of the sleeve; resilient means on the sleeve having frictional contact with the socket for holding the same in adjusted position, and resilient means on the block having frictional contact with the sleeve for holding the same in adjusted position. 90
2. In a lamp including a reflector and a lamp bulb cooperating with the reflector, the combination with a socket adapted to receive the lamp bulb; of means supporting the socket, including a sleeve member and a support member in which the sleeve is rotatably mounted on an axis eccentric to the axis of the socket, whereby relative rotation of said sleeve member and the support member effect lateral adjustment of the socket and bulb carried thereby; and means for yieldingly maintaining the relative adjustment of said sleeve member and support member, and holding the same assembled, including friction elements supported on one of said members and having both shouldered and frictional engagement with the other of said members and means mounted on the member on which said elements are supported for yieldingly forcing said elements against the member with which the friction elements engage. 105
3. In a lamp including a reflector and a lamp bulb cooperating with the reflector, the combination with a sleeve adapted to receive the base of said lamp bulb; of a supporting member for said sleeve, in which the sleeve 110

is mounted for rotation on an axis eccentric to the axis of said lamp bulb to effect lateral adjustment of the lamp bulb, said sleeve having an annular groove; and means for yieldingly holding said sleeve in adjusted position including friction elements mounted on said supporting member and engaging within said groove, and spring members also mounted on said supporting member for yieldingly holding said elements in said groove.

4. In a lamp including a reflector and a lamp bulb cooperating with the reflector, the combination with a sleeve in which the base portion of the lamp bulb is supported; of a support for the sleeve in which the sleeve is rotatably mounted on an axis eccentric to the axis of the lamp bulb, to effect lateral adjustment of the bulb with respect to the center of the reflector to focus said bulb, said sleeve having shouldered engagement with the support to limit movement of the sleeve lengthwise in one direction; and means for yieldingly holding said sleeve in adjusted position, including a friction element having camming engagement with the sleeve to hold the same in shouldered engagement with the support, thereby preventing looseness therebetween.

5. In a lamp including a reflector and a lamp bulb cooperating with the reflector, the combination with a holder for the lamp bulb; of a support for the holder provided with an opening adapted to receive the holder and in which the same is adjustably mounted; a flange on said holder abutting said support to prevent movement of the sleeve in one direction; and yielding means having camming engagement with said holder for forcing the flange thereof against the support and maintaining the same engaged therewith.

6. In a lamp including a reflector and a lamp bulb cooperating with the reflector, the combination with a sleeve adapted to support said lamp bulb; of a support in which said sleeve is mounted for rotation about an axis eccentric to the axis of said bulb to provide for lateral adjustment of the bulb with respect to the center of the reflector, said sleeve having an annular bearing flange engaging the support to limit axial movement of the sleeve in one direction; and means for preventing accidental relative rotation of the sleeve and support, including an annular groove on said sleeve having a curved bottom wall, and spring pressed elements engaging with said sleeve, said elements having rounded end portions having frictional contact with the wall of the groove and engaging within said groove to one side of the center of the same, thereby yieldingly holding said flange in engagement with the support.

In witness that I claim the foregoing I have hereunto subscribed my name this 25th day of May, 1928.
